UNITED STATES PATENT OFFICE.

ALEXANDER HAMILTON, OF NEW YORK, N. Y.

HAND-PUMP.

SPECIFICATION forming part of Letters Patent No. 246,880, dated September 13, 1881.

Application filed October 1, 1880. (Model.)

To all whom it may concern:

Be it known that I, ALEXANDER HAMILTON, of the city, county, and State of New York, have invented a new and useful Improvement 5 in Hand-Pumps, of which the following is a specification.

Figure 1 is a side elevation of the improvement, partly in section. Fig. 2 is a sectional elevation of the upper valve and the parts of 10 the cylinders with which it is connected, enlarged.

Similar letters of reference indicate corresponding parts.

The object of this invention is to furnish 15 hand or portable pumps for sprinkling plants and trees with water or other liquid, for putting out fires, washing carriages, windows, and sidewalks, and for other purposes, so constructed that it can be adjusted to throw a jet, 20 a spray, both a jet and a spray, and to shut off the water.

A represents a hose, to one end of which is attached a small filter or screen, B, to prevent 25 impurities from being drawn into the pump and clogging the valves. The other end of the hose A is attached to a nipple formed upon the cap C, screwed upon the end of the outer pump-cylinder, D, forming a valve-chamber.

Within the cap or valve-chamber C is placed 30 a valve, E, opening upward to admit water to the pump, and to prevent the water from being forced back into the reservoir. The valve E is kept in line by its stem passing through a bar or perforated plate placed in the upper 35 part of the chamber C, and is held down to its seat, except when forced upward by the pressure of the entering water, by a spring placed upon its stem and interposed between the said valve and its guide-bar.

40 Within the cylinder D is placed a cylinder, F, of such a size that the capacity of the said cylinder F shall be equal to the capacity of the ring-space or water-chamber f between the two cylinders D F. The inner cylinder, F, is 45 made to work water-tight through the forward end of the outer cylinder, D, by a stuffing-box, G, attached to the end of the said cylinder D.

To the inner end of the inner cylinder, F, is secured, by a screw, pin, or rivet, H, a cap, I, 50 having a tube or hollow neck, J, upon its lower part. The cap I is made of such a size that

the water will have a free passage-way between it and the outer cylinder, D. To the end of the neck J of the cap I is attached, or upon it is formed, the bottom of a water-way cup, K, which bottom has a number of apertures, L, formed through it, around the end of the neck J, the combined area of which apertures L is equal to the area of the cavity of the neck J of the cap I, so that the amount of water that 55 passes through the neck J into the cylinder F will be equal to the amount of water that passes through the apertures L into the space or water-chamber between the cylinders D F. The lower part of the cup K is made smaller than 60 the upper part, and upon the outer surface of the said smaller part is formed a screw-thread, g, to fit into a screw-thread, h, cut in the inner surface of the sides of the valve-chamber M. In the bottom of the chamber M is formed an 65 aperture, the sides of which are beveled to form a seat for the valve N. The valve N is kept in line by its stem, which passes through a guide-hole in a bar attached to the water-way cup K, and is held closed, except when opened 70 by the pressure of the water, by a spring placed upon the valve-stem between the valve and the guide-bar.

The cap I and the water-way cup K and the valve-chamber M are centered in the cylinder 80 D by ring-flanges formed upon them, and which fit against the inner surface of the said cylinder D, and are made to work water-tight by a packing, O, clamped against the bottom of the chamber M by a plate, P, secured to the said 85 bottom by screws.

With this construction, when the inner cylinder, F, is drawn outward the tendency is to form a vacuum in the lower part of the outer cylinder, D, which causes the air-pressure upon 90 the surface of the water in the reservoir to force the water through the hose A, causing the water to open the valve E and pass into and fill the cylinder D. As the inner cylinder, F, is forced inward the pressure upon the water 95 thus produced closes the valve E, opens the valve N, and causes the water to pass into and fill the inner cylinder, F, and the space or water-chamber between the cylinders D F. As the inner cylinder, F, is again drawn outward 100 the water again opens the valve E and fills the cylinder D, and the water between the cylin-

ders D F is forced through the apertures L and neck J into the cylinder F, forcing the water already in the said cylinder F out at the upper end of the said cylinder F, producing a discharge. As the inner cylinder, F, is again forced inward the pressure upon the water in the cylinder D closes the valve E and forces the water through the valve N into the space or water-chamber between the cylinders D F, filling it, and into the inner cylinder, F, forcing the water already in the cylinder F out through the upper end of the said cylinder F, again producing a discharge. This construction causes the pump to throw a continuous stream, or makes it double-acting.

I am aware that a portable force-pump has heretofore been constructed of an outer barrel having valves at its lower end and inclosed by an exterior casing to form a water-chamber, a hollow rod or tube being arranged within the outer barrel and working through a stuffing-box at the end thereof, the inner end of said hollow rod or tube being contracted to form a tubular neck, on which is arranged a movable piston, said neck being perforated to admit water between the outer barrel and the hollow rod or tube, the said piston being arranged to slide on the contracted neck to alternately open and close the perforations therein as the piston is raised and lowered, as in United States Patent No. 199,380; but such structure is not claimed by me, and does not constitute my invention, an important feature of which consists in providing a piston which is fixed in relation to the inner cylinder, and in so arranging the apertures which connect the valve-chamber and the intervening space between the inner and outer cylinders that they remain permanently or at all times open for the passage of water; and, further, in so constructing and arranging the apertures around the neck which connects with the inner cylinder that the combined area of said apertures is equal to the passage through said neck, so that equal amounts of water pass through the apertures and through the neck, and thereby equal amounts of water will be ejected through the inner cylinder at both strokes of the piston.

Having thus fully described my invention, I

claim as new and desire to secure by Letters 50 Patent—

1. In a portable hand-pump, the combination, with the outer cylinder, D, having a valve, E, and the inner cylinder, F, passing through a stuffing-box, G, and arranged to provide the intervening water-space, of the cap I, rigidly attached to the end of the inner cylinder and having a contracted neck, J, the cup K, attached to said neck and having in its top a series of apertures, L, arranged around the neck, and which remain permanently open for the passage of water, and the valve-chamber connected to the cup and containing a spring-valve and formed at one end into a piston, all substantially as described. 65

2. The combination, with the outer and inner cylinders arranged to provide the intervening water-space f, of the cap I, having the contracted tubular neck J, communicating with the inner cylinder, the cup K, having a series 70 of apertures, L, arranged around the neck, and which remain permanently open for the passage of water to the space f, and the valve-chamber M, containing a valve, N, and constructed with a rigid piston, the combined area 75 of the said apertures L being equal to the passage through the tubular neck J, as and for the purposes herein set forth.

3. The combination, with the outer cylinder, D, having a valve, E, at its lower end, and the inner cylinder, F, arranged to provide the intervening space f, of the cap I, rigidly attached to the end of the inner cylinder and having a contracted neck, J, the cup K, attached to said neck and constructed with a series of apertures, 80 L, arranged around the neck, and which remain permanently open for the passage of water to the space f, the valve-chamber M, connected with the said cup and provided with a valve, N, and a fixed piston, the valve-chamber and cup being provided with ring-flanges 85 to center them in the outer cylinder, all substantially as herein described. 90

ALEXANDER HAMILTON.
